LEVELING AND ALIGNING MEANS

Albert M. Guillet, Charlotte, N. C.

Application February 25, 1946, Serial No. 649,991

4 Claims. (Cl. 33—84)

1

This invention relates to a leveling and aligning means for machinery and especially a machine such as a Foster winder.

Heretofore, I have developed various means for leveling and aligning spinning frames and the like, such as disclosed in my Patent No. 1,907,959 dated May 9, 1933, in which the reel and reel support means, shown in the present application, are more fully disclosed and described.

It is an object of this invention to provide means whereby the reel mechanism, shown in my said patent, can be used in the leveling and aligning of types of machines, other than those disclosed in said patent such as Foster winders.

It is an object of this invention to provide mechanism for attaching to opposed ends of a Foster winder for supporting leveling and aligning means for proper leveling and aligning the machinery for the use of my improved apparatus.

It is another object of this invention to provide special brackets and mechanism for attaching to opposed ends of a winding machine and the like for supporting a reel at one end and an anchoring means at another end for stretching a wire or other line from the anchoring means to the reel means where proper tension can be supplied to the line, and the line is used as a guide in the leveling and aligning of the entire machine.

Some of the objects of the invention having been stated, other objects will appear as the description proceeds when taken in connection with the accompanying drawings in which:

Figure 1 is a top plan view of a portion of a Foster winder, more especially the model 102 winder with the top or creel portion broken away and center portions of the machine broken away;

Figure 2 is a front elevation of the structure shown in Figure 1 with the top or creel portion and the bottom portion of the machine being broken away;

Figure 3 is a view similar to Figure 1, but showing only the two end portions of the machine on an enlarged scale, and with the central portion of the machine being broken away. The upper right hand portion of Figure 3, being taken at a lower level than the upper right hand portion of Figure 1;

Figure 4 is a view similar to Figure 2, but on an enlarged scale, and having the greater portion of the center portion of the machine broken away;

Figure 5 is an end view looking from the right hand end, and towards the left in Figures 1, 2, 3, and 4;

Figure 6 is a vertical sectional view taken along the line 6—6 in Figure 4;

2

Figure 7 is a sectional view taken along the line 7—7 in Figure 1;

Figure 8 is a sectional view taken along the line 8—8 in Figure 5;

Figure 9 is a vertical sectional view taken substantially along the line 9—9 in Figure 6;

Figure 10 is an isometric view of the anchoring means in looking from the left hand side of the anchorage means as shown in Figure 6.

Referring more specifically to the drawings, the numeral 10 indicates the head end of a Foster winder, which contains driving mechanism for driving two shafts which are a front shaft 11, and a rear shaft 12. These shafts have a plurality of rollers 13 thereon. These rollers support suitable cheeses onto which the yarn is wound by driving the cheeses by frictional contact. The left hand end of the roller shafts 11 and 12 are mounted in suitable bearings 15 and 16 in the side wall of the head portion 10 and project into the head portion 10 where, by suitable gearing not shown, they are driven. The right hand end of the rollers 11 and 12 are mounted for rotation in bearings 16 and 17 and they are supported for rotation in suitable bearing housing 18 intermediate their ends. The framework of the machine is generally designated by reference character 20 and there are uprisers 21 which support a suitable creel mechanism, not shown.

30 In order to properly level and align the various portions of the machine, I have devised means for attaching certain brackets and other fixtures to the framework and head of the machine for supporting a reel at one end and an anchor member at the other end. For supporting the anchor member, I provide a bracket 25, which is secured to the head of the machine by means of a conventional bolt 26, and this bracket projects outwardly and then laterally, and extends downwardly and has a semi-circular cut away portion therein as at 21, more especially shown on Figure 6, which fits against one side of shaft 11.

There is another portion 28 having a semi-circular portion adapted to fit against the other side 45 of the shaft 11 and a suitable set screw 29 is slidably mounted in portion 28 and threadably mounted in the bracket 25, whereby the downwardly projecting portion can be clamped around the shaft 11 to secure that portion of the bracket 50 in position.

This bracket 25 has a vertically disposed notch 30 therein, which on its outer face next to the head 10 of the machine has a pair of transverse grooves 31 and 32. Adapted to fit into the outer 55 portion of notch 30 is an anchor bracket 35 which

has upper laterally projecting ribs 36 and 37, which are adapted to rest in the groove 31. The anchor bracket 35 has an inwardly projecting portion whose right hand surface in Figures 1-3 projects into the notch 30, and thus is slidably mounted for vertical movement in the notch 30, when the ribs 36 and 37 are removed from the groove 31. The groove 32 is provided so as to allow the lower end of the anchor bracket 35 to rest on the lower face of this groove whereas the lower right hand end of this bracket, as viewed in Figure 3, will rest against the vertical portion of the groove 32 since the groove 32 is just below the lower end of notch 30, as will be observed in Figure 9.

The anchor bracket 35 has a pair of projections 40 and 41 in which a thumb screw 42 is loosely mounted, said thumb screw being confined in these projections 40 and 41 by means of a collar 43, the lower end of the thumb screw 42 being bradded or peened over the collar 43 to confine the thumb screw in the projections 40 and 41. The thumb screw is threaded intermediate its ends, and threadably penetrates a wire anchor member 45, which projects to the right in Figures 1, 2, 3, 4, and 9, and has a cap 46 disposed thereon. The upper edge of the portion 45 and the lower surface of cap 46 have semi-circular grooves therein forming a cavity 47 through which a wire, such as a piano wire 48, passes, said wire encircling a screw 49 which slidably penetrates the cap 46 and is threadably mounted in the portion 45 to thus confine the ends of the reel wire 48 in position on the anchoring member.

Secured to the other end of the machine is a bracket 50 by means of bolts 51 and 52, said bracket having a cutaway portion 53 so that it will fit over a rib 54, which is a part of the conventional framework of the machine. This bracket 50 has secured thereon, by means of a bolt 55, an upstanding bracket 56, which is outwardly turned at its upper end, as at 57, and the upper end portion has a semi-circular cavity 58 therein in which the semi-circular portion of a bracket 59 is mounted. This bracket 59 has a downwardly projecting portion 60 on its left hand end thereof in which is threadably mounted a thumb screw 61 which has a follower 62 on its right hand end, as in Figure 4 for example, which is adapted to press against the left hand face of bracket 56, as seen in Figure 4.

The right hand end of the bracket 59 in Figures 3 and 4 has on opposed sides thereof vertically disposed slots, in which the inwardly projecting portions 65 are slidably mounted, said inwardly projecting portions 65 being integral with a bracket 66, which has an inwardly projecting tongue, not shown, in which a thumb screw 67 is threadably mounted, said thumb screw being rotatably mounted in the bracket 59, as more fully disclosed in my above referred to patent. This permits vertical adjustment of the bracket 66 relative to bracket 59. Bracket 66 has a horizontally projecting portion 66a on which is fixed a dove tailed slide 68 on which reel housing 69 is mounted, and the reel housing being laterally slideable on the dove tailed guideway 68 and a suitable thumb screw 70 is threadably mounted in portion 66a and slidably penetrates dove tailed member 68, and is adapted to press against the reel housing 69 to lock it in laterally adjusted position. This reel housing 69 has mounted therein a suitable reel, not shown, on which the other end of wire 48 is fixedly mounted, so that when the reel is turned in one direction, the wire will

be tautened and when turned in the other direction, it will be loosened. The reel has a peripheral worm gear thereon, which is engaged by suitable worm mounted on a thumb screw 75, the reel is also fixedly mounted on a shaft 76 rotatably mounted in each side of the reel housing and on one side of this shaft 76 is secured a crank member 77 for imparting rotation to the reel. The thumb screw 75 can be used also for imparting rotation to the reel in slight degrees, but is largely used in locking the reel in position. When it is screwed upwardly out of contact with the worm gear on the reel, it allows the reel to be turned by the crank 77, but when screwed down into position to engage the worm gear on the reel, it locks the worm gear in the position to which it has been turned by the crank 77. All of the structure of the reel housing, bracket 57 and the like, are fully disclosed in my Patent No. 1,907,959.

Also for leveling and alining the machine, I have provided a plurality of collars 80, each having a notch or cavity 81 therein, adapted to fit over the shafts 11 and 12, and a thumb screw 82 is provided in each of these collars 80 for affixing the collars 80 to the shafts 11 and 12. Incidentally, these collars 80 are exactly the same diameter as the rolls 13 of the shafts 11 and 12, on which the cheeses rest for a winding operation. With a plurality of these collars in position, I can place a leveling member 85 with its ends resting on the collars 80, and this level has a bracket 86 on one end thereof, adapted to rest against one of the collars 80, so as to place it in the right position. This level has a downwardly bent central portion indicated at 87 for missing a rod 88, which is a conventional portion of the machine. The level member 85 has a spirit level 89 mounted on one end thereof, so that with the level member 85 placed in either the bold line position, shown in the left hand end of Figure 1, or in dotted line positions, as shown along other portions of the rolls 13, it can be determined whether or not the level of the rolls at that portion of the machine is correct. The end of the level member 85, which is placed beneath the wire 48, is cut away, as at 90 and 91, leaving a rib 92, having a transverse slot 93 therein, in which the wire 48 is adapted to be centered in an alining and leveling operation.

The reel housing 69 has resiliently mounted pins 94, which press against the upright portion of bracket 66, as more completely shown in my said patent.

In the drawings and specifications, there has been set forth a preferred embodiment of the invention and although specific terms are employed, they are used in a generic and descriptive sense only, and not for purposes of limitation, the scope of the invention being defined in the claims.

I claim:

1. A leveling and alining apparatus comprising a bracket attachable to one end of a winding frame and having a depression in its upper end, a reel bracket adapted to fit into said depression, means on the reel bracket for clamping the reel bracket to the upper end of the first named bracket, a vertically adjustable reel housing disposed on said second bracket, and having a line extending therefrom, a third bracket attachable to the other end of the frame, and having a vertically disposed slot in its upper end, said third bracket having a pair of spaced horizontally disposed parallel grooves in the outer face thereof, a fitting adapted to fit into said slot and having a pair of laterally extending portions on each

side adapted to fit into said grooves, a vertically disposed threaded screw mounted in said fitting and having a line anchor threadably mounted thereon and extending into said slot in the upper end of third bracket, said anchor having a means thereon for anchoring the other end of the line extending from the reel housing, said winding frame having a pair of horizontally disposed parallel shafts having rolls thereon, cylindrical members attachable to said shafts, a level member adapted to rest on said cylindrical members or on said rolls, one end of said level having a downwardly projecting portion adapted to fit against one of said cylindrical members or rolls, said level having a transverse slot in its upper edge adapted to coincide with the line extending from the anchor to said reel housing.

2. A leveling and alining apparatus for a winder frame having a pair of parallel horizontally disposed shafts, said apparatus comprising a bracket secured to one end of the frame and projecting laterally across and above one of said shafts, a vertically disposed notch in the upper edge of the bracket, a fitting adapted to fit loosely into said notch, said fitting having a turnable threaded member vertically disposed therein, a line anchor member threadably disposed on the vertically threaded member and having means for anchoring one end of a line thereto, a second bracket mounted on the other end of the winding frame and extending upwardly and having a reel housing attached thereto, a line extending from said reel housing and anchored to said anchor member at the other end of the frame, said parallel shafts having a plurality of rollers fixedly secured thereon for contacting cheeses for rotating the same, said parallel shafts also having a pair of collars secured thereon near each of the one ends of the shafts, a transverse member adapted to rest on said rollers and on said collars as desired, the collars being of the same diameter as the rollers, means on the transverse member for engaging one of the collars or a roller when the transverse member is placed thereon for positioning the transverse member relative to the roller, one end of the transverse member having a transverse notch therein which is adapted to coincide with the line extending between the anchor member and the reel housing when the machine is in perfect alinement.

3. Apparatus for alining and leveling winding frames comprising a bracket having means for attaching it to one end of the frame and having means on its upper end for supporting a reel housing from which a line is adapted to extend, a second bracket attachable to the other end of the frame, said frame having a pair of spaced parallel revolving shafts thereon having spaced rollers thereon for contacting cheeses or imparting rotation thereto during a winding operation, said second bracket having a downwardly projecting portion and a clamping member associated therewith whereby the second bracket can be clamped around one of said shafts, said second

bracket having a notch cut in its upper end and extending downwardly thereinto, said second bracket having parallel spaced grooves in its outer edge, a fitting adapted to fit into said notch and having transversely extending portions adapted to fit into said grooves, said fitting having a turnable vertically disposed threaded screw therein, an anchor member threadably mounted on said screw whereby by rotating said screw the anchor member will be adjusted vertically of the notch in which it is disposed, said anchor member having means for securing the other end of said line extending from the reel housing thereto, each of said shafts having fixed thereon a collar, each collar being of the same dimensions as rollers on which cheeses are adapted to rest, a transverse member adapted to rest on said collars, or said rollers as desired, said transverse member having a downwardly projecting portion adapted to fit against one side of one of the collars or the rollers to position the transverse member relative to the two shafts, said transverse member having a transverse notch therein adapted to become alined with the line extending from the anchor member to the reel housing when the shafts, collars and rollers are in perfectly alined position.

4. A leveling and alining means for a winder frame comprising a bracket attachable to one end of the frame and having means for supporting a reel housing with a line extending from the reel housing, a second bracket attachable to the other end of the frame, said frame having a pair of parallel shafts therein, each of said shafts having rollers mounted thereon, the second bracket having clamping means for engaging one of the parallel shafts, said second bracket having a vertically adjustable anchor member disposed therein to which the other end of said line may be secured, and means on the second bracket for vertically adjusting the position of the anchor member relative to the bracket, a transverse member adapted to span the distance between and rest on the rollers of said two shafts and said transverse member having a transversely disposed notch therein adapted to coincide with and to receive the line extending between the reel housing and the anchor member when the rollers and shafts are in properly alined position.
